US00D880459S

(12) **United States Design Patent** (10) **Patent No.:** **US D880,459 S**
Su (45) **Date of Patent:** **** Apr. 7, 2020**

(54) **MICROPHONE**

(71) Applicant: **Shenzhen Hua Sirui Technology Co. Ltd.**, Shenzhen, Guangdong Province (CN)

(72) Inventor: **Kuo Su**, Shenzhen (CN)

(**) Term: **15 Years**

(21) Appl. No.: **29/674,398**

(22) Filed: **Dec. 20, 2018**

(51) **LOC (12) Cl.** **14-01**

(52) **U.S. Cl.**

USPC **D14/226**

(58) **Field of Classification Search**

USPC D14/226, 225, 228, 218, 188, 196, 160, D14/165, 167, 189, 210, 215, 216; D21/513; 84/454, 610, 609; 381/111, 381/113, 355, 359, 360, 361, 122, 188, 381/205, 158; 455/95, 117, 129, 90.3, 455/575.1, 569.1

(57) **CLAIM**

The ornamental design of a microphone, as shown and described.

DESCRIPTION

FIG. 1 is a front perspective view of a microphone, showing my new design;

FIG. 2 is a front bottom perspective view thereof;

FIG. 3 is a rear bottom perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The broken lines depict environment that forms no part of the claimed design.

1 Claim, 9 Drawing Sheets
